UNITED STATES PATENT OFFICE.

ERNEST J. ROWE, OF HELENA, MONTANA.

PANTOGRAPHIC APPARATUS.

Application filed January 21, 1928. Serial No. 248,444.

This invention relates to theatrical apparatus and more particularly to the construction and control of an animated dummy to permit duplication of certain operations performed by a concealed operator.

An important object of the invention is to provide an apparatus whereby a dummy may duplicate cartoons or other drawings delineated by the concealed operator.

10 A still further object of the invention is to produce mechanism for accomplishing these objects which is extremely simple in both its construction and operation, which is readily manipulated and which will be durable and efficient in-service.

15 These and other objects I attain by the construction shown in the accompanying drawings, wherein for the purpose of illustration is shown a preferred embodiment of my invention and wherein:—

Figure 1 is a side elevation partially in section showing theatrical apparatus constructed in accordance with my invention;

20 Figure 2 is a section on the line 2—2 of Figure 1, the dummy being illustrated in dotted lines;

Figure 3 is a section on the line 3—3 of Figure 1;

25 Figure 4 is a plan view of the operator's arm mechanism showing the coaction with the pattern;

Figure 5 is a detail sectional view through one end of the control mechanism;

30 Referring now more particularly to the drawings, the numerals 10 and 11 indicate operator's and dummy's easels, of which the operator's easel has clips 11' for interchangeably supporting panels 12 upon which patterns 13 are produced for the guidance of the operator. Below the panel, the easel 10 has secured to one leg thereof a guide element 14, the purpose of which will presently appear.

35 The easel 11 has mounted thereon a transparent panel 15 and has secured thereto at its upper end and at its rear face a rotatable roller 16 supporting a paper roll 17, the web from which is passed over the upper end of the easel and downwardly over the front face thereof and thence beneath the lower end of the panel 15 to a winding roller 18. This winding roller has at one end thereof a worm gear 19. Secured to the easel 11 at a point corresponding to the position of the guide 14 of the easel 10 is a container 20, for the reception of ink or paint.

The easels 10 and 11 are preferably arranged adjacent opposite ends of a platform 21 and arising from this platform are standards 22 suitably braced to one another and to the platform. These supports are arranged adjacent the easels 10 and 11 and the support adjacent the easel 10 has secured thereto a bracket 23, through which is rotatably directed a shaft 24 having at its rear end a crank 25, and at its forward end, which is rotatably directed through a bracket 26 carried by the easel 11, a worm 27 for engagement with the worm gear 19 of the winding roll 18, so that this winding roll may be rotated to draw paper from the paper roll 17. The roll 16 supporting the paper roll has at its end a ratchet disk 28 and the adjacent bracket 29 by means of which this roll is supported from the easel 11 mounts a pawl 30 releasable by a string 31 extended adjacent the easel 10, by means of 70 which the roll may be locked against rotation. As the worm gearing employed for the operation of the winding roll likewise serves to lock this roll, it will be obvious that the paper may be drawn tightly across the face of the 75 easel and secured in this position.

80 The upper ends of the supports 22 have extending upwardly therefrom spaced guides 32 between which at a point spaced below the upper ends thereof are rollers 33. Mounted upon these rollers between the guides 32 is an assemblage comprising inner and outer tubular shafts 34 and 35, of which the inner shaft 34 is of greater length than the shaft 35 and has its ends extended beyond the ends thereof. The outer shaft 35 has secured thereto spaced stop collars 36 coaxing with one of the pairs of guides to limit longitudinal movement of the assemblage over the rollers. It will be obvious that this assemblage may 85 be either rotated or longitudinally shifted within the limits defined by these stop collars. In order to reduce frictional contact between the inner and outer shafts 34 and 35, the shaft 34 is preferably of less external diameter than the internal diameter of the shaft 35 and the shaft 35 has mounted in its ends bushings 37 in which the shaft 34 may be rotated. The outer ends of the shaft 34 have secured thereto an upper arm element 90 95 100 105 110 115 120 125 130 135 140 145 150 155 160 165 170 175 180 185 190 195 200 205 210 215 220 225 230 235 240 245 arms 41 connected by links 42 to the forearm structure 40 at a point spaced from the pivot 39 thereof, so that rotation of the shaft 35, while the shaft 34 is stationary, will result in 5 an oscillation of the forearm elements 40 about their pivots 39. It will, of course, be obvious that movement of the forearm or upper arm elements 38 or 40 at either end of the structure will be duplicated at the opposite end of the structure. The arm structure at the forward end of the easel 11 is incorporated in and concealed by the clothing of a dummy 43. The end of the forearm structure is formed as the hand of the dummy 15 and constructed to support a brush or stylus 44. The forearm element adjacent the easel 10 is provided with a stylus 45 constructed to co-operate with the pattern 13. The pattern 13 employed is preferably provided by a groove or rib formed upon the panel 12 in the 20 desired shape. The easel 10 and the associated arm mechanism may be concealed within a booth 46 which may also conceal operating mechanism controlling other movements of the dummy other than the arm movements (not herein shown).

The use of the apparatus is as follows: The operator concealed within the booth 46 engages the pointer and first moves the same 30 into the guide 14, with the result that the stylus of the dummy is dipped into the container 20. The stylus 45 is then moved to the pattern and passed thereover. The operator through a suitably formed opening 35 in the booth wall and through the transparent panel 15 may observe the progress of the reproduction and in event of failure of the fluid of the stylus 44, may again dip this stylus into the container 20 to replenish the 40 same. The pattern completed, the web may be shifted to present a clean surface by manipulation of the crank.

It will be obvious that in moving the stylus 44 from the container 20 to the sheet, the entire mechanism should be shifted outwardly, 45 so that this stylus will not contact the sheet until it arrives at the proper point.

Since the construction hereinbefore set forth is capable of a certain range of change and modification without materially departing from the spirit of the invention, I do not limit myself to such specific structure except as hereinafter claimed.

I claim:

55 1. In a pantographic apparatus, a pair of panels one bearing a pattern and the other a sheet upon which the pattern is to be reproduced, a pair of concentric tubes, relatively long arms secured to the respective ends of one of said tubes, forearm elements pivoted to the ends of said arms, respectively, relatively short arms secured to the respective ends of the other of said tubes, links connecting the ends of each short arm to its adjacent 60 forearm element whereby similar movements 65 are transmitted to said forearm elements, and styli carried by said elements for movement over the respective panels.

are transmitted to said forearm elements, and styli carried by said elements for movement over the respective panels.

2. In a pantographic apparatus, a pair of panels one bearing a pattern and the other a sheet upon which the pattern is to be reproduced, a pair of concentric tubes, relatively long arms secured to the respective ends of one of said tubes, forearm elements pivoted to the ends of said arms, respectively, relatively short arms secured to the respective ends of the other of said tubes, links connecting the ends of each short arm to its adjacent forearm element whereby similar movements are transmitted to said forearm elements, styli carried by said elements for movement over the respective panels, a cabinet enclosing the panel bearing the pattern and the associated arm mechanisms of the tubes and a dummy in an arm of which the arm mechanism at the opposite ends of the tubes is included.

3. In a pantographic apparatus, a pair of panels one bearing a pattern and the other a sheet upon which the pattern is to be reproduced, a pair of concentric tubes, relatively long arms secured to the respective ends of one of said tubes, forearm elements pivoted to the ends of said arms, respectively, relatively short arms secured to the respective ends of the other of said tubes, links connecting the ends of each short arm to its adjacent forearm element whereby similar movements are transmitted to said forearm elements, styli carried by said elements for movement over the respective panels, an easel supporting each panel, a container carried by the easel of the sheet bearing panel and into which the stylus of the associated arm mechanism may be extended and a guide carried by the other of the easels into which the stylus of the associated arm mechanism is engaged to cause engagement of the stylus of the first named arm mechanism in said container.

4. In a pantographic apparatus, a pair of panels one bearing a pattern and the other a sheet upon which the pattern is to be reproduced, a pair of concentric tubes, relatively long arms secured to the respective ends of one of said tubes, forearm elements pivoted to the ends of said arms, respectively, relatively short arms secured to the respective ends of the other of said tubes, links connecting the ends of each short arm to its adjacent forearm element whereby similar movements are transmitted to said forearm elements, styli carried by said elements for movement over the respective panels, a cabinet enclosing the panel bearing the pattern and the associated arm mechanisms of the tubes, a dummy in an arm of which the arm mechanism at the opposite ends of the tubes is included, an easel supporting each panel, a container carried by the easel of the sheet bearing panel and into which the stylus of the associated 130

arm mechanism may be extended, and a guide carried by the other of the easels into which the stylus of the associated arm mechanism is engaged to cause engagement of the stylus 5 of the first named arm mechanism in said container.

5. In a pantographic apparatus, a pair of panels one bearing a pattern and the other a sheet upon which the pattern is to be reproduced, a pair of concentric tubes, relatively long arms secured to the respective ends of one of said tubes, forearm elements pivoted to the ends of said arms, respectively, relatively short arms secured to the respective ends of 15 the other of said tubes, links connecting the ends of each short arm to its adjacent forearm element whereby similar movements are transmitted to said forearm elements, stylus carried by said elements for movement over 20 the respective panels, an easel supporting each panel, a container carried by the easel of the sheet bearing panel and into which the stylus of the associated arm mechanism may be extended, a guide carried by the other of 25 the easels into which the stylus of the associated arm mechanism is engaged to cause engagement of the stylus of the first named arm mechanism in said container, and a mounting for said tubes in which the tubes are rotatable 30 and longitudinally shiftable.

6. In a pantographic apparatus, a pair of panels one bearing a pattern and the other a sheet upon which the pattern is to be reproduced, a pair of concentric tubes, relatively long arms secured to the respective ends of one of said tubes, forearm elements pivoted to the ends of said arms, respectively, relatively short arms secured to the respective ends of the other of said tubes, links connecting the 35 ends of each short arm to its adjacent forearm element whereby similar movements are transmitted to said forearm elements, stylus carried by said elements for movement over the respective panels, a cabinet enclosing the 40 panel bearing the pattern and the associated arm mechanisms of the tubes, a dummy in an arm of which the arm mechanism at the opposite ends of the tubes is included, an easel supporting each panel, a container carried by the 45 easel of the sheet bearing panel and into which the stylus of the associated arm mechanism may be extended, a guide carried by the other of the easels into which the stylus of the associated arm mechanism is engaged to cause engagement 50 of the stylus of the first named arm mechanism in said container, and a mounting for said tubes in which the tubes are rotatable and longitudinally shiftable.

7. In a pantographic apparatus, a pair of panels one bearing a pattern and the other a sheet upon which the pattern is to be reproduced, a pair of concentric tubes, relatively long arms secured to the respective ends of one of said tubes, forearm elements pivoted 55 to the ends of said arms, respectively, rela-

tively short arms secured to the respective ends of the other of said tubes, links connecting the ends of each short arm to its adjacent forearm element whereby similar movements are transmitted to said forearm elements, stylus carried by said elements for movement over the respective panels, and a mounting for said tubes in which the tubes are rotatable and longitudinally shiftable. 70

8. In a pantographic apparatus, a pair of panels one bearing a pattern and the other a sheet upon which the pattern is to be reproduced, a pair of concentric tubes, relatively long arms secured to the respective ends of one of said tubes, forearm elements pivoted to the ends of said arms, respectively, relatively short arms secured to the respective ends of the other of said tubes, links connecting the ends of each short arm to its adjacent forearm element whereby similar movements are transmitted to said forearm elements, stylus carried by said elements for movement over the respective panels, a cabinet enclosing the panel bearing the pattern and the associated arm mechanisms of the tubes, a dummy in an arm of which the arm mechanism at the opposite ends of the tubes is included, and a mounting for said tubes in which the tubes are rotatable and longitudinally shiftable. 85

9. In a pantographic apparatus, a pair of panels one bearing a pattern and the other a sheet upon which the pattern is to be reproduced, a pair of concentric tubes, relatively long arms secured to the respective ends of one of said tubes, forearm elements pivoted to the ends of said arms, respectively, relatively short arms secured to the respective ends of the other of said tubes, links connecting the ends of each short arm to its adjacent forearm element whereby similar movements are transmitted to said forearm elements, stylus carried by said elements for movement over the respective panels, a cabinet enclosing the panel bearing the pattern and the associated arm mechanisms of the tubes, a dummy in an arm of which the arm mechanism at the opposite ends of the tubes is included, said sheet being the web of a roll supported from the associated panel, a winding roll at the rear of the panel at the opposite end thereof from the first named roll, means releasable from the cabinet for locking the first named roll against rotation, and means operable from the cabinet for rotating the winding roll to advance the sheet over the panel. 90

10. In a pantographic apparatus, a pair of panels one bearing a pattern and the other a sheet upon which the pattern is to be reproduced, a pair of concentric tubes, relatively long arms secured to the respective ends of one of said tubes, forearm elements pivoted to the ends of said arms, respectively, relatively short arms secured to the respective ends of the other of said tubes, links connecting the ends of each short arm to its ad- 115

5 jacent forearm element whereby similar movements are transmitted to said forearm elements, styli carried by said elements for movement over the respective panels, a cabinet enclosing the panel bearing the pattern and the associated arm mechanisms of the tubes, a dummy in an arm of which the arm mechanism at the opposite ends of the tubes is included, said sheet being the web of a roll
10 supported from the associated panel, a winding roll at the rear of the panel at the oppo-

site end thereof from the first named roll, means releasable from the cabinet for locking the first named roll against rotation, and means operable from the cabinet for rotating 15 the winding roll to advance the sheet over the panel, the last named means locking the winding roll against rotation when not in operation.

In testimony whereof I hereunto affix my 20
signature.

ERNEST J. ROWE.
